UNITED STATES PATENT OFFICE.

JOHN PRIESPILIS, OF BROOKLYN, NEW YORK.

GRAMOPHONE RECORD BRUSH.

1,414,302.

Specification of Letters Patent. Patented Apr. 25, 1922.

Application filed June 5, 1920. Serial No. 386,672.

To all whom it may concern:

Be it known that I, JOHN PRIESPILIS, a citizen of Lithuania, residing at Brooklyn, county of Kings, and State of New York, 5 have invented certain new and useful Improvements in Gramophone Record Brushes, of which the following is a specification.

My invention relates to brushes for cleaning phonograph record plates or the like, 10 and has for its object to produce a brush of this character of simple inexpensive construction adapted to keep the record grooves clear of dust and the tiny shavings produced by the needle, while reproducing a 15 record.

A further object of the invention is to provide means for elastically mounting the brush in such manner that it will readily follow the needle and yield when meeting 20 obstructions or uneven spots.

Another object of the invention is to provide a brush which is adjustably mounted and allows a securing of the brush to tune arms of varying diameter.

25 With these and other objects hereinafter explained in view, my invention consists in the construction hereinafter described and claimed.

Referring to the drawing—
30 Figure 1 is a side view of a record plate, sound box, needle and tune arm with the brush constructed according to my invention mounted thereon.

Figure 2 is an enlarged detail view partly 35 in section taken along line 2—2 of Figure 1.

Figure 3 is a top plan view of a guide strip.

In the drawing, 10 indicates a record 40 plate, 11 a needle, 12 the sound-box and 13 a tune arm mounted in a socket 14, all parts described so far being constructed in the ordinary well known manner and forming no part of the present invention.

45 To the arm 13 is secured its length by means of a split or open ring 15 in which a smaller ring 16 is contained, provided with a point 17, an adjustable supporting

rod 18 which can be adjusted by means of a screw 19 within a longitudinally and vertically arranged sleeve 20 on the extension 50 21 of the larger ring 15. Underneath the arm 13 the open ends of the split rings 15 and 16 are connected by means of an adjusting screw 22.

55 The end of the rod 18 is extended through a longitudinal slot 23 of a guide strip 24 and carries therebelow a head or block 25.

The oppositely disposed end of the strip 24 is bent to form a U-member 26 and is 60 provided with an opening in alignment with a similar opening in the U-member. Through both openings the stem 27 of a brush 28 is passed carrying at its upper end an adjusting screw nut 29. Between 65 the brush head 30 and the lower face of the U-member a coiled spring 31 is wound around the stem.

The operation of the device will be clear 70 from the above description of the same on hand of the drawing.

It will of course be understood that I do not desire to be limited to the precise construction or arrangement shown or described, it being clear that the brush could 75 be mounted in front of the needle, and that other changes in details of construction and arrangement can be made without departing from the spirit of the invention.

Having thus described my invention, what 80 I claim and desire to secure by Letters Patent of the United States is as follows—

A mounting for a phonograph record brush comprising a support, a stem for said brush, a horizontal slotted and perforated 85 guide strip, a perforated U-member at one end of said strip allowing the passage of the free end of said stem, a set screw on the upper end of said stem, a coiled spring wound around said stem between said 90 brush and said U-member, said slotted portion co-operating with said support for adjustably securing said guide strip.

In testimony whereof I have affixed my signature.

JOHN PRIESPILIS.
